SWITCHING AND SIGNALING MECHANISM

Albert Koch Andriano, New York, N. Y.

Application June 10, 1933, Serial No. 675,210

28 Claims. (Cl. 179—90)

This invention relates to intercommunicating systems, as between telephones or other instruments, and with respect to its more specific features to switching indicating and control mechanism in conjunction with such systems.

The invention also relates to improvements in dials or indicators and in signaling and switching devices and circuit controlling means for electrical signaling and power units and for telephone systems of the kind in which each telephone or station is provided with means for obtaining direct communication with another station without a central exchange.

One of the objects of this invention is the provision of a switching and signaling mechanism which can be quickly and simply operated and which practically eliminates all danger of erroneous operation.

Another object is the provision, in a device of the above character, of a dial or plate having a point of rest, or station, indicated thereon by characters or numerals so arranged that they can be read in any direction.

The invention also has for its object a novel construction of switching and connecting means and signaling devices for telephones of this character; to provide a dial that when rotated in either direction (to right or left) at all times shows the numbers, letters or other designations on the dial in readable (upright) position; to simplify and combine the operation of the switching and signaling device so that connection is made with any selected circuit or station and the selected station or unit is signaled with one rotary motion.

A further object is the provision in a telephone system of a practical switch for use with a telephone station which may be used in connecting that station with any other station in the system and which may be left in any position upon the completion of the call without preventing that station from receiving calls from other stations.

Another object is to provide a satisfactory rotary switch which may be employed in many different associations and which may be selectively operated to close any one of a plurality of switches without danger of confusion on the part of the operator.

A further object is the provision of a stop for a shiftable switch which serves to restrain further shifting of said switch and which will serve further as a circuit closer.

Among other objects is the provision of a novel signaling and switching mechanism for a tele-

phone system, the operation of which may not be completed until the receiver is removed from the hook, which has figures or dial numbers that are always in readable position, and which has a signaling key which serves as a stop member for the dial and is a circuit closer to complete the circuit between the telephone stations.

A further object is to provide a compact unitary dialing mechanism which may readily be attached to any telephone base, parts of which are individually rugged, which may be economically constructed, and which will operate over long periods of time with freedom from repairs.

Further objects will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and objects of the invention, reference should be had to the following detailed description taken in connection with the accompanying drawings, in which:

Fig. 1 is a side elevation, partly in section, of a desk telephone and a switching and signaling device attached thereto, both embodying certain features of the present invention;

Fig. 2 is a plan view, partially fragmentary, of a dialing mechanism such as is employed on the base of the telephone in Fig. 1, showing the finger plate, screen, dial plate, ratchet, and signaling key;

Fig. 3 is a side elevation of a portion of a telephone, with the casing broken away showing the receiver hook in depressed position as when the receiver is on the hook and showing also a novel switch and latch arrangement embodying certain features of the present invention;

Fig. 4 is a side elevation in detail of the lower portion of the mechanism disclosed in Fig. 3, showing the novel latch arrangement which operates in response to the receiver hook;

Fig. 5 is a side elevation similar to Fig. 3, showing the receiver hook in elevated position as when the receiver is removed.

Fig. 6 is a plan view of a portion of a dial switch and telephone base taken along the line 6—6 of Fig. 1, and showing in detail the signaling key;

Fig. 7 is a plan view of the contact base and switching mechanism controlled by the dial;

Fig. 8 is a plan view of the dial plate, screen,

and finger hole plate, with portions partially broken away so as to reveal the novel arrangement of the numbers on the dial and the construction of the screen;

5 Fig. 9 is a plan view of a modified form of dial plate, screen, and finger hole plate, embodying certain features of the present invention, showing the numbers, screen, and finger hole plate arranged in a different manner;

10 Fig. 10 is a plan view of another form of dial plate, screen, and finger hole plate, embodying features of the present invention;

15 Fig. 11 is a diagrammatic representation of a telephone system of the direct line type, showing a novel switching and signaling mechanism embodying features of the present invention; and

20 Fig. 12 is a diagrammatic representation of a signaling system or circuit, embodying features of the present invention.

25 Referring now more specifically to Figures 1 through 5, the numeral 1 indicates a telephone, and 2 indicates generally a dial switch, both of which embody certain of the features of the present invention. The telephone illustrated is of the type generally known as a desk set, and comprises transmitter or mouthpiece 4, base 3, and the upright connecting portion 5. A plate 7 extends through the upright portion and is secured in position by suitable fastening means such as rivet 47. A screw 6 secured to the plate retains the bottom of the telephone in position. The plate 7 is formed with an opening 29 and pivoted at this point and extending through the opening and through the outer casing of the 30 telephone is a receiver hook such as lever or arm 8, which is preferably formed at its outer end with a bifurcated hook (not shown) for retaining a telephone receiver. This may be of the conventional type usually employed on a telephone 35 desk set. At the opposite end of the member 8 is an extension 9 which is preferably formed with a protrusion 10 formed of insulating material for engaging the switch mechanism—which will be described later. A rod 11 extends along the 40 inside of the casing of the telephone from the member 8 into the base portion. The rod is supported so as to permit of longitudinal shift movement. This may be accomplished by having the rod loosely supported by two posts, shown 45 at 12 and 13, secured to the plate 7 and to the side or casing of the telephone. A spring 14 normally forces the rod 11 upward so as to press the receiver hook 8 upwardly and retain it in the position shown in Figure 5. However, when 50 the receiver is placed upon the hook, the weight thereof is sufficient to counteract the pressure of the spring and to force the lever 8 and the rod 11 downward into the position shown in Figure 3. Secured to the lower end of the plate 7 is a member 15 which serves as a supporting plate 55 for the latch mechanism about to be described. The member 15 is formed with a horizontal base 16 to which is fastened a plate 17. The plate 17 is formed with two extensions or legs 17' and 17''. Pivoted between the lobes or ears 18 formed on the two extensions or legs of the member 17 is a 60 latch mechanism 19. The latch mechanism has three separate parts, a rearwardly extending lever 20, the latch piece 21 and a dog 22. The lever 20 extends rearwardly into the path of movement of the rod 11 and when the receiver is upon the hook 8 the rod 11 is pressed downwardly and engages the lever 20, causing the members 21 and 22 to assume the positions shown 65 in Figure 3. Extending between the dog member

22 and the extension 23 on the bottom of plate 15 is a spring 24. It will be seen that when the receiver is removed from the hook, spring 14 will push the rod 11 into elevated position. The end of rod 11 will move out of engagement with the lever 20 and spring 24 will cause the member 22 and 21 to assume the position shown in Figure 4. The dog member 22 is so formed that when the receiver is on the hook it extends above the surface of the plate 17 so as to serve as a block or stop to resist any lateral movement of the member 24. The latch member 21 is preferably longer than the dog 22 so that when the receiver is removed from the hook it will normally rest upon the member 24, as shown in Figure 4.

15 Fastened to the middle portion of plate 7 is the block 25, having three contact springs 26, 27 and 28 mounted thereon. The springs are so arranged that contact 27 is normally in engagement with contact 28 and out of engagement with contact 26, as shown in Figure 5. However, the contact spring 27 is formed with an extension which is engaged by the protrusion 10 formed on the end of the receiver hook 8. When the receiver is on its hook, the extension on member 27 will be engaged by the protrusion 10 and contact 27 will be forced out of engagement with the contact 28 and into engagement with the contact 26, as shown in Figure 3. When the receiver is removed from the hook, however, the pressure upon the spring 27 by the protrusion 10 will cease, and the contacts will again return to their normal positions, as shown in Figure 5.

35 The latch mechanism and switch mechanism heretofore described are illustrated in the accompanying drawings in association with a telephone of the type commonly known as a desk set. However, it is to be understood that it is within the purview of this invention to employ a latch mechanism and switch mechanism of this type in any type of telephone, such as a French telephone or a wall telephone. In each instance the mechanisms will operate in response to depression and release of the receiver holder.

40 The novel dialing or rotary switch mechanism is disclosed at 2 in Fig. 1 and in detail in Fig. 2 and in Figs. 6 through 10. While the mechanism hereinafter described is illustrated in association with a telephone, and while it is especially suited for use in a telephone system, it is nevertheless within the purview of certain aspects of the present invention to employ such a switch in other types of electrical circuits such as the signaling system illustrated in Fig. 12.

45 The dialing mechanism is preferably formed with a central pivot 30. On the bottom of the pivot is an adjustable collar 31 which may be held in place by a set screw 32. The top of the pivot is preferably formed with a threaded opening into which is introduced the screw 33. It is preferred that certain portions of the pivot be circular in cross section so members may be rotatably mounted thereon and that other portions be irregular or rectangular in cross-section so that 50 members may conveniently be fixedly mounted thereon. Fixedly mounted on the pivot is the dial plate 34. This is preferably formed with an opening at its center, generally rectangular in shape so as to cooperate with a rectangular portion of the central pivot member. Because of this construction, rotation of the pivot member will cause rotation of the dial member. On the dial plate are symbols as the numerals indicated by 55 60, each indicating a different station or point 70 75

of rest of the switch, or, in the case of a telephone system, each numeral representing a telephone station in the system. These numerals are so arranged that a numeral for each station of the switch will always be in readable position.

In Fig. 2 and Fig. 8 of the accompanying drawings, this is accomplished by placing two concentric rows of figures on the dial plate so as to form a plurality of pairs of figures. That is, there are two number ones, one disposed nearer the edge than the other. Likewise, there are two number twos, threes, etc., disposed in similar relation. In this modification each point of rest of the switch, or each station in a telephone system, will be represented by a pair of the same number. In Figs. 2 and 8 the inner row is in upright position from the edge of the dial, while the outer row is in upright position from the center of the dial. It will be seen that on the lower half of the dial, the inner row of figures appears in readable position, while on the upper half of the dial the outer row of figures appears in readable position. If the dial is rotated, it will be seen that the figures on the top portion of the dial in readable position become in non-readable position as they enter the lower half of the path of rotation and those in non-readable position become in readable position. Likewise, the position of the figures on the lower portion of the dial is reversed as they are rotated to the top portion.

In Fig. 9, the numerals or characters on plate 34 are arranged generally as in Figs. 2 and 8. However, the inner row of figures is spaced at a greater distance from the outer row so that the figures of each pair will be farther apart. This arrangement will permit of a variation of the structure of the screen and finger hole plate, which will be described later.

In Fig. 10, the figures are illustrated as appearing in pairs. The pairs of figures, however, instead of forming two concentric rows as in the previous illustration, are arranged so that two of the same figures are placed side by side. One figure in each pair is disposed in inverted relation to the other figure of the pair. It will be seen that as the dial is rotated, one of the figures of each pair will always be in readable position. The figure in readable position at the top of the dial will be in non-readable position as it is rotated to the bottom. Likewise, the figure in non-readable position at the top will be in readable position when rotated to the bottom. In the modifications illustrated in the accompanying drawings, each station is indicated by a pair of numbers, one in inverted relation to the other. Upon rotation of the dial, there will always be one figure in each pair in readable position. At no time will both figures in a pair be inverted below horizontal position.

Of course it is to be understood that many variations may be made in the arrangement of the characters or numbers on the dial without departing from the present invention. Instead of using a pair of figures as shown in the accompanying drawings, a plurality of figures such as three or four may be employed, each readable in different directions. It is to be understood also that while the accompanying drawings show numbers on the dial plate, other symbols or characters, such for example as letters, may be employed.

It is within the purview of certain aspects of this invention that the dial plate herein de-

scribed may be used alone and not in association with the screen and finger hole plate described hereinafter. When used alone, it will be seen that a character or number representing each of the points of rest or stations of the dial will be in readable position when viewed from any angle.

It is preferred, however, that a screen 35 be disposed above the dial member. This serves to conceal the symbol or number in each pair not in readable position and to display the number in each pair in readable position. It is formed with openings 36 which reveal the numbers or characters in readable position. Solid shielding portions 37 are disposed so as to conceal the characters not in readable position. The screen is fixedly mounted so that it may not rotate with the pivot 30 or the dial 34. This may be accomplished by forming the shielding portions out of an integral sheet of metal with three extensions 20, 38 fastened by means of screws 39 to plate 55, which in turn is made fast to the base of the telephone as hereinafter described. To secure additional support the screen may be formed with a central portion loosely engaging the central 25 pivot, but not fixedly mounted thereon.

In the modifications illustrated in Figs. 2, 8 and 9, the screen is formed so that the openings reveal the outer row of figures on the top row of the dial and the inner row of figures on the bottom portion of the dial and the shielding portion covers the inner row of figures on the top portion of the dial and the outer row of figures on the lower portion of the dial. In the modification shown in Fig. 10, the openings 36 are preferably in the form 35 of a semi-circle, the openings at the upper portion of the screen being complementary to the openings on the lower portion of the screen.

In all of the modifications illustrated the screen is stationary. The screen is so formed that solid 40 shielding portions will conceal the symbols or numbers in non-readable position during every portion of the shift path of the dial and will reveal the numbers in readable position in every portion of the shift path. It will be seen now that 45 as the dial is rotated from station to station, the figures exposed to view will always be in readable position. Those in non-readable position will be concealed by the shielding portions 37 of the screen 35. 50

Disposed above the screen and fixedly mounted on the pivot 30 is the dial operator or finger hole plate 40. Rotation of the finger hole plate will cause rotation of the pivot and of the dial plate 34. The finger hole plate is formed with 55 a series of openings or orifices arranged so that each opening appears above a character on the dial member. In the modifications shown in Figs. 2, 8 and 10, a pair of the same figures appear under each opening. However, the screen serves to conceal the figure in each pair not in readable position. In the modification illustrated in Fig. 9, in addition to the openings 41, the finger hole plate is formed with windows or openings 42. On the upper portion of the dial the figures in normal 60 reading position are seen through the finger hole openings 41 and on the lower portion of the dial the figures are seen through the windows 42. 65

To operate the mechanism heretofore described a finger is inserted in the finger hole appearing above the number of the desired station and the 70 plate is rotated until the finger engages the stop 72. Rotation of the finger hole plate causes rotation of the pivot and of the dial plate. For instance, if the operator wishes to make connection with station number eight of a telephone 75

system, he inserts his finger in the hole of the plate 40 appearing above the number 8 and rotates the plate until his finger engages the stop 72. It will be seen that during all stages of the operation, there will always be a number in readable position for each station.

Loosely mounted on the bottom of the pivot 30 is the contact support 45. This is formed of an insulating material and is preferably fixed at three points 46, by means of screws 41 passing through spacers 40, to the base of the telephone so that it cannot rotate with the pivot. Mounted on the contact base are a series of contact points 48', 48'', 48''', etc., and when used in a telephone system as shown in Fig. 11, each one of these contact points is connected to the circuit of a telephone station, or, when used in a signaling system, as in Fig. 12, to a signaling circuit, as will be later described. A circular contact 49 is also fixed to the contact base. Immediately above the contact base is a switch bar or contact arm 50. This is fixedly mounted to the central pivot 30 by means of a suitable fastener such as set screw 51. One end of the contact strip indicated at 52, is preferably arranged so as to continuously engage the circular contact 49 and the other end indicated by the number 53 is arranged so as to successively engage the contact points 48', 48'', 48''' as the switch bar is rotated.

It will be seen that if the finger hole plate is rotated as described above, the pivot will be rotated and consequently the dial and the switch bar 50. This will cause the switch bar to successively engage the contacts 48', 48'', etc. It is preferred that the dial member should have a numeral or symbol to represent each of the contacts 48', 48'', etc. The numbers are so arranged on the dial that when the number 1 is adjacent the stop key 72, the switch arm is in engagement with the contact point represented by the number 48'. If the operator should desire to close the circuit between the contact 49 and the contact point 48'', all that he has to do is to insert his finger in the finger hole appearing above the number 2 and rotate the finger hole plate 50 until his finger engages the stop key 72. The circuit will then be closed. Because of the novel arrangement of the numbers and because of the construction of the screen, a number representing each of the stations or contacts will always be in readable position. When the finger hole plate is rotated so that the dial numbers appear in different relative positions, they will nevertheless always appear to the operator in readable position. This serves to eliminate confusion and errors which normally would result therefrom.

Turning again to the construction of the dial switch, the numerals 55 and 56 represent two plates with central apertures loosely engaging pivot 30. They are held against rotation with the pivot by being fixedly mounted on the telephone base at points 65 by means of screws 44 and 66 which are threaded into spacer members 43 and 67 respectively. It will be observed that the screws 44 pass directly through portions 68 of the telephone base and serve to firmly hold the spacer members 67 and 43 thereto. The plates 55 and 56 serve to support the central pivot, and as a mounting for several stationary parts such as the screen, pawl and spring.

If desired, a ratchet wheel 71 may be secured to the undersurface of the dial plate 34 or may be fixedly mounted on the pivot 30 in order to prevent the dial switch from rotating in both directions. If the ratchet is employed, a pawl 69 pressed by the spring 70 may be mounted on the fixed plate 66 so as to engage the teeth of the

ratchet wheel 71 as illustrated in Fig. 2. Under this construction the dial switch may only be operated in a clockwise direction, the pawl and ratchet serving to prevent counterclockwise rotation.

A stop, or signaling key 72 is provided immediately above the finger hole plate, and as previously described, serves to engage the finger and stop further rotation when the contact to the selected station has been closed. When used in a telephone system, it may serve also as a signaling key to ring the bell of the selected station. To accomplish this it has an arm 73 formed with an aperture loosely encircling the central pivot 30 so as not to rotate therewith. At its opposite end it is formed with an extension 74 previously referred to which projects into the telephone base and normally rests adjacent the latch mechanism in the telephone base. Disposed between the latch mechanism and the central pivot 30 and adjacent to the arm 73 is a contact block 75. This contact block 75 is preferably formed of a plurality of contact strips 76, 77, 78, 79, 80 and 81, fastened together by a series of insulating blocks 75' which in turn are mounted on the contact base 45. The strips are so formed that normally contact strip 77 is out of engagement with contact strip 76 and in engagement with contact strip 78, and contact strip 80 is normally in engagement with contact strip 79 and out of engagement with contact strip 81. However, contact strips 77 and 80 are formed with extensions 77' and 80' which are in position to be engaged by the arm 73 if pressure is exerted on the key 72 to shift that arm. The arm 73 is suitably insulated where it comes in contact with extensions 77' and 80'.

Dog 22 of the latch mechanism, previously described, serves to restrain shifting of the arm 73 when the receiver hook of the telephone is depressed. When the receiver hook is depressed, the dog 22 is in the position shown in Fig. 3 and if pressure is exerted upon the key 72 the arm 73 will be restrained from shifting because the dog 22 engages extension 74. When the receiver is removed from the hook, the spring 24 will remove dog 22 from the path of movement of arm 73, as shown in Fig. 4. If pressure is then exerted on the key 72, the arm 73 will shift inwardly into engagement with the contact strip extensions 77' and 80', forcing the contact 77 out of engagement with contact 78 and into engagement with contact 76 and forcing contact 80 out of engagement with contact 79 and into engagement with contact 81.

A coiled spring 85 anchored to the stationary plate 55 engages the arm 73, serving to return the arm 73 and key 72 to their normal position when pressure is released upon the key 72. However, the latch piece 21 will prevent the arm 73 from fully returning to its normal position. It will engage the extension 74 and retain it in the position indicated in Fig. 5. The contact strip extension 77' is preferably shorter than the contact strip extension 80' and the latch 21 is long enough to permit the arm 73 to be shifted by the spring 85 so that it will no longer be in engagement with extension 77', but will still be in engagement with 80'. Contact 77 will then return to its normal position, that is, out of engagement with contact 76 and in engagement with contact 78. Contact 80 will remain in engagement with contact 81 and out of engagement with contact 79.

When the receiver hook 8 is depressed, as when the receiver is returned to the hook, the latch 21 will be elevated, due to the pressure on lever 20 75

5 by rod 11, and the parts will again return to the position illustrated in Fig. 3. The arm 73 will then be out of engagement with the extension 80' and contact 80 will again engage contact 79 and be free from engagement with contact 81.

In order to more thoroughly understand the operation of the novel latching, switching and dialing mechanism heretofore described, reference may be had to Figure 11, which shows an 10 embodiment of the present invention in association with a telephone system.

Figure 11 is a diagrammatic representation of a telephone system of the direct line type, i. e., 15 communication between the stations of that system is not made through a central exchange, but is made directly between the stations. The system disclosed has two stations, indicated generally as station I and station II. A suitable 20 source of current supply for the talking circuit such as battery 80 is connected, by means of line 81 to common return line 82 and thence to the transmitter 130 of station I, and to the transmitter 131 of station II. The line 84 connects the source of current supply to impedance coils 25 85 and 86, which are connected by lines 87 and 88, respectively, to lines 89 and 90. Line 89 is connected to the contact strip 79 of station I, and line 90 is connected to contact strip 79 of station II. The contact strip 27 of station I is connected 30 by means of line 91 to contact 78; likewise, contact strip 27 of station II is connected by means of wire 92 to contact strip 78 of that station. Contact strip 28 of station I is connected 35 by means of wire 93 to the primary of induction coil 135 and then to the transmitter, and the contact strip 28 of station II is connected by means of wire 94 to the primary of induction coil 136 which in turn is connected to the transmitter of that station. Contact strip 81 of station I is connected to a circular contact 49 by means of a line 95, and contact strip 81 of station II is connected by means of wire 96 to circular contact 49 of that station. The contact point 48' of station I is connected by means of wire 97 to the line 90 leading to contact strip 79 of station II. Contact 45 point 48' of station II is connected by means of wire 98 to line 89, which leads to contact strip 79 of station I.

Another source of current supply such as battery 99 serves to energize the signaling mechanisms of the stations which consist, in the present case, of the bells 100 and 101. Line 102 connects one terminal of the battery to lines 103 and 104, which supply one post of the signaling bells 100 and 101. Another line 105 connects the other side of the current supply to lines 106 and 107. Line 106 is connected to the contact strip 76 of station I and line 107 is connected to the contact strip 76 of station II.

Each station of the telephone system has the novel latching arrangement 19, switch block 25, dialing mechanism 2, signaling key 72, switch mechanism 75, all of which has been described heretofore. The telephone system disclosed in Figure 11 is operated as follows:—A station desiring to call another station must first remove the receiver from the hook so that the receiver hook 8 assumes an elevated position. In Figure 11 the receiver of station I has been removed from the hook. If the operator of station I desires to call station II, he inserts his finger in the hole of the finger hole plate appearing above the numeral 2 and revolves the plate until his finger 70 is engaged by the stop or signaling key 72. The

switch bar 50 is then connected between circular contact 49 and the contact 48'' as in Figure 11 at station I. Pressure is then exerted on the member 72 in the direction of rotation of the dial, that is, in a clockwise direction. Because the receiver is off the hook, the rod 11 is in elevated position and the stop 22 is not in the path of movement of extension 74 of arm 73. The arm 73 will thereafter shift in response to pressure on the key 72 into contact with the contact strip 10 extensions 77' and 80', causing contact strip 77 to move out of engagement with contact strip 78 and into engagement with contact strip 76, and the contact strip 80 out of engagement with the contact strip 79 and into engagement with the 15 contact strip 81. This will cause the current from battery 99 to flow through wires 105, 106, contact strips 76, 77, wire 110, contact strip 80 through contact strip 81, through wire 95 to circular contact 49; through switch bar 50 to contact 48''; and by means of wires 97 and 90 to contact strip 79 of station II. Contact strip 79 is in engagement with contact strip 80 and accordingly the current will pass through contact strip 80, wire 111, contact strip 77, contact strip 25 78, wire 92, contact strip 27, contact strip 26, wire 113 to one post of the signaling bell 101 and thence through wires 104 and 102 back to the battery 99, thereby completing the circuit to the 30 signaling bell of station II. Figure 11 portrays the stations during this state of the operation. The receiver of station I has been removed from the hook, the dial has been rotated to select station II, and pressure has been exerted on stop key or signaling key 72 to ring the bell of station II. 35 When station II responds to the ringing of its bell and removes its receiver from the hook 8, the contact strip 27 will move out of engagement with the contact strip 26 and into engagement with contact 40 28, thereby breaking the circuit to the 40 signaling bell 101, which will accordingly stop ringing.

After ringing the bell, the operator of station I will release pressure upon the stop 72, then arm 73 will be moved by means of circular spring 45 85 so that it will be out of engagement with contact strip extension 77'. However, the latch 21 will retain the member 74 so that arm 73 will remain in engagement with the contact strip extension 80'. Contact strip 77 will then be in engagement with contact strip 78, but out of engagement with contact strip 76, and the circuit of the signaling bell of station II will thus be broken in a second place. Contact strip 80 will remain in engagement with contact strip 81 and 50 out of engagement with contact strip 79. The talking circuit between the two stations will now be completed. Transmitter of station I is connected through the primary circuit of induction coil 135 to wire 93, contact strip 28, contact strip 55 27, wire 91, contact strip 78, contact strip 77, wire 110, contact strip 80, contact strip 81, wire 95, circular contact 49, switch bar 50, contact 48'', wires 97 and 90, contact strips 79 and 80 of station II, wire 11, contact strip 77 and 78, wire 92, 60 65 contact strips 27 and 28, and wire 94 to the primary circuit of induction coil 136 to the transmitter of station II, and thence by means of common return wire 82 back to the transmitter of 70 station I.

As previously stated, the battery 80 is connected by means of wire 81 to the common return wire 82 and by means of wire 84 to the impedance coils 85 and 86, which in turn are con- 75

5 nected by the wires 87 and 88 to lines 89 and 90. The talking circuit between the two stations has therefore been completed. When the conversation between the two stations has been completed, the receivers are replaced upon the hooks 8 which will accordingly be depressed. At station II contact strip 27 will be forced out of engagement with contact strip 28 and into engagement with contact strip 26. Station II will once 10 again be in condition to receive any incoming calls. At station I, when the receiver hook 8 is depressed, contact strip 27 will likewise be forced out of contact with contact strip 28 and into engagement with contact strip 26. The rod 11 will 15 also be depressed, forcing the lever 20 downwardly. The latch 21 will accordingly be raised and spring 85 will return the arm 73 to its normal position which is indicated at station II. Contact strip 80 will accordingly be released by 20 the arm 73 and will move out of engagement with contact strip 81 and into engagement with contact strip 79. Station I will now be in condition to receive any incoming calls. Any station may 25 call another station by following the procedure outlined above. While in Fig. 11 but two stations are illustrated in the system, it is to be understood that any number of stations may be employed. The rotary or dial switching mechanism 2 will have a contact point 48 for each of the 30 other stations in the system. The contact point for each station will be connected to the direct line of that station.

35 It will be observed that in the present circuit it is immaterial what position the dial switch is left in upon completing a call. In other words, after conversation between two stations has been completed, it is not necessary to return the dialing switch to any particular position in order to receive an incoming call. This is true because 40 incoming calls are not received through the dial switch 2, but are received by a direct line, in the case of station I, line 89, and in the case of station II, line 90, each connected to its respective station through switch blocks 75. Outgoing calls, 45 however, are made through the dialing switch, each station in the system will have a contact 48' etc., connected to the direct line of the other stations of the system, and by rotating the dial switch, connection can be made to the direct line 50 of any other station in the system.

55 Figure 12 is a diagrammatic representation of a signaling system employing a novel dialing or rotary switching mechanism embodying certain aspects of the present invention. One of the terminals of a source of current supply, such as battery 115, is connected by means of wires 121 and 122 to one post of a signaling bell 126 and by means of wires 121 and 123 to a post of signaling light 127. The other post of signaling bell 60 126 is connected by means of wire 124 to contact point 48'. The other post of the signaling light is connected by means of wire 125 to contact point 48''. The circular contact 49 is connected by means of wire 120 to contact strip 118. Contact strip 117 is connected by wire 116 to the other terminal of battery 115. The mechanism is operated as follows:—If the operator wishes to 65 ring the bell 126, he inserts his finger in the finger hole above the symbol on the dial plate representing that bell. For purposes of illustration we will say that 1 indicates the signaling bell and 2 the light. He will then rotate the finger hole plate in a clockwise direction until his finger engages the stop 72. The switch bar 50 will then 70 be in the position shown in Fig. 12, i. e., connected

75 between circular contact 49 and contact point 48'. The operator then exerts pressure upon the stop 72 to force the contact strip 118 into engagement with the contact strip 117, thereby closing the circuit to the signaling bell 126 which will accordingly ring. If the operator wishes to 80 light the light 127, he will insert his finger in the finger hole appearing above the numeral 2, rotate the dial, and follow the procedure just described. Of course, any number of signaling circuits may be employed.

85 It will be seen from the above illustrations that the novel switching and dialing mechanism may be used in association with many different types of circuits such as signaling, communicat- 90 ing, or power circuits.

95 Since certain changes may be made in the above construction and different embodiments of the invention could be made without departing from the scope thereof, it is intended that all 100 matter contained in the above description or shown in the accompanying drawings shall be interpreted as illustrative and not in a limiting sense.

Having described my invention, what I claim 105 as new and desire to secure by Letters Patent is:—

1. A dial for a rotary switch comprising, in combination, a member mounted for rotary shift movement, and symbols on said member to indicate the various stations of said switch, said symbols being arranged so that a symbol for each station is always in readable position for each station position of the dial. 110

2. A dial for a rotary switch comprising, in combination, a member mounted for rotary shift movement, and symbols on said member to indicate the various stations of said switch, each of said stations being represented by a plurality of the same symbol each readable in a different di- 115 rection. 40

3. A dial for a rotary switch comprising, in combination, a member mounted for rotary shift movement, and a plurality of symbols on said member to indicate one station of said switch, each of said symbols being readable in a different direction. 45

4. A device of the character described comprising, a member shiftable from station to station, and a plurality of numbers on said member indicating the same station, each of said numbers being readable in a different direction. 50

5. A device of the character described comprising a member shiftable from station to station having two like numbers indicating the same 55 station, one of said numbers being arranged in inverted relation to the other, and means cooperable to display one of said numbers in readable position when the other is in non-readable position. 60

6. A device of the character described comprising a member shiftable from station to station having two like numbers indicating the same station, one of said numbers being arranged in inverted relation to the other, and means cooperable to display one or the other of said numbers in readable position at all stations of said member. 65

7. A device of the character described comprising, in combination, a dial member shiftable 70 from station to station, a plurality of like numbers on said dial indicating the same station, means cooperable to display one of said numbers in readable position at one point of the shift path of said dial and to display another of said num- 75

bers in readable position at another point in the shift path of said dial.

8. A device of the character described comprising, in combination, a member rotatably shiftable from station to station, and two like numbers on said dial indicating the same station, one of said numbers being arranged in inverted relation to the other.

9. A device of the character described comprising, in combination, a member rotatably shiftable from station to station, two like numbers on said dial indicating the same station, one of said numbers being arranged in inverted relation to the other so that upon shifting of said dial one number will change from readable to non-readable position and the other from non-readable to readable position, and means cooperable to screen from view the number in non-readable position.

10. A device of the character described comprising, in combination, a number dial rotatably shiftable from station to station, and a light-screen disposed adjacent said dial.

11. A device of the character described comprising, in combination, a dial rotatably shiftable from station to station, and a screen disposed adjacent said dial, said dial having two concentric series of station numbers and said screen being cooperable at one part of the dial to cover numbers of one of said series while permitting view of the numbers of the other series at said part and at another part of the dial to cover numbers of the last mentioned series while permitting view of numbers of the other series at said other part.

12. A device of the character described comprising, in combination, a dial rotatably shiftable from station to station, a screen disposed adjacent said dial, said dial having two concentric series of station numbers and said screen being cooperable at one part of the dial to cover numbers of one of said series while permitting view of the numbers of the other series at said part and at another part of the dial to cover numbers of the last mentioned series while permitting view of numbers of the other series at said other part, and a finger hole plate rotatably shiftable with said dial.

13. A device of the character described comprising, in combination, a number dial mounted, for rotary shift movement, a finger hole plate cooperable to cause rotary shift of said dial, and a stationary screen interposed between said finger hole plate and said dial and cooperable to conceal some of the numbers thereon.

14. A device of the character described comprising, in combination, a dial member mounted for rotary shift, a finger plate having a plurality of finger holes cooperable to cause rotation of said dial member, and a pair of numerals disposed on said dial member beneath each of said finger holes, both of the numerals in any one pair being the same but in inverted relation to each other.

15. A dial switch for use in a telephone system having a plurality of stations comprising, in combination, a rotatably shiftable member, means acting in response to shifting of said member for connecting one station to another station, and symbols on said member to indicate points of connection with different stations, said symbols being arranged so that a symbol for each station is always in readable position.

16. A dial switch for use in a telephone system having a plurality of stations comprising, in combination, a rotatably shiftable member for

connecting one station to another, symbols on said member to indicate the point of connection with each of said stations, each of said points of connection being represented by a plurality of the same symbol each readable in a different direction, and means for concealing those symbols for each point not in readable position.

17. A dial switch for use in a telephone system having a plurality of stations comprising, in combination, a rotatably shiftable member for connecting one station to another, symbols on said member to indicate the point of connection with each of said stations, each of said points of connection being represented by a pair of the same symbols, one readable in one direction and the other readable in another direction, and means for concealing the symbols readable in one direction on one segment of said member and for concealing the symbols readable in the other direction on the remaining segment of said member.

18. A dial switch for use in a telephone system having a plurality of stations comprising, in combination, a rotatably shiftable member, means responsive to shifting of said member to connect one station with any one of the other stations, a plurality of pairs of visible symbols on said shiftable member, each pair indicating a point of connection with a different station, one symbol of each pair being disposed nearer the center of said member and being in readable position from the edge thereof, and the other symbol of each pair being disposed nearer the edge of said member and being readable from the center thereof, and means comprising a stationary screen cooperable to conceal the symbols disposed nearer the center of said member on one portion thereof and for concealing the symbols disposed nearer the edge on the remaining portion of said member so that a symbol for each station will always be in readable position.

19. A device of the character described comprising, in combination, a shiftable switch member, a circuit closer, and means disposed in the path of movement of said switch member cooperable to operate said circuit closer upon shifting of said switch member.

20. A device of the character described for use with the station in a telephone system having a plurality of stations each with a signaling bell comprising, in combination, a finger operated switch member for connecting said first mentioned station with another station, a stop for engaging the finger when the switch has been operated to connect said two stations, and means cooperable to operate upon the application of pressure to said stop in the direction of movement of said switch to ring the bell of said last mentioned station.

21. A device of the character described for use with the station in a telephone system having a plurality of stations each with a signaling bell comprising, in combination, a finger operated switch member for connecting said first mentioned station with another station, a stop for engaging the finger when the switch has been operated to connect said two stations, means cooperable upon the application of pressure to said stop in the direction of movement of said switch to ring the bell of said last mentioned station, and means operable upon releasing the pressure on said stop to close the circuit between said stations.

22. A device of the character described for use with the station in a telephone system having a plurality of stations each with a signaling bell comprising, in combination, a finger operated rotary dial switch for connecting said first men-

- tioned station with another station, means comprising a pawl and ratchet cooperable to prevent rotation of said switch in one direction, a stop for engaging the finger when the switch has 5 been operated to connect said two stations, and means cooperable upon the application of pressure to said stop in the direction of movement of said switch to ring the bell of said last mentioned station.
- 10 23. A device of the character described comprising, in combination, a shaft, a finger plate, a number plate, and a screen positioned intermediate said finger plate and said number plate, said finger plate and number plate being mounted 15 on said shaft so that rotation of the finger plate will cause rotation of the number plate.
24. A device of the character described comprising, in combination, a shaft, a finger plate and a number plate disposed around said shaft so as 20 to rotate therewith, a screen loosely mounted on said shaft and interposed between said finger plate and number plate, and means cooperable to prevent said screen from rotating with said shaft.
- 25 25. A dial switch for a telephone system having a plurality of stations comprising, in combination, a shaft, a finger plate for rotating said shaft, a dial member mounted on said shaft to rotate therewith, a plurality of numbers on said dial indicating each of the stations, and a screen interposed between said finger plate and number plate so as to conceal some of the numbers.
- 30 26. A dial switch for a telephone system having a plurality of stations comprising, in combination, a shaft, a finger plate for rotating said shaft, a dial member mounted on said shaft to rotate therewith, two numbers on said dial indicating one of said stations, one being in readable position and one in non-readable position, and a screen disposed around said shaft and fixed against rotation therewith for concealing the number in inverted position.
- 35 27. A dial switch for use in a telephone system having a plurality of stations comprising, in combination, a central pivot, a finger hole plate
- 40 mounted on said pivot and cooperable to cause rotation thereof, a dial member fixedly mounted on said pivot so that rotation of the pivot will cause rotation of the dial member, a contact base loosely encircling said pivot and fixed against rotation therewith, a plurality of contact points each having connection with a station of the telephone system mounted on said contact base, a contact arm fixedly mounted on said pivot and cooperable to successively engage said contact 10 points upon rotation of said pivot, a plurality of pairs of numerals on said dial member each pair indicating a station, one numeral of each pair being in inverted relation to the other numeral of that pair, and means comprising a screen disposed around said pivot and fixed against rotation therewith for concealing the numerals not in normal reading position.
- 45 28. A dial switch for use in a telephone system having a plurality of stations comprising, in combination, a central pivot, a finger hole plate mounted on said pivot and cooperable to cause rotation thereof, a dial member fixedly mounted on said pivot so that rotation of the pivot will cause rotation of the dial member, a contact base 20 loosely encircling said pivot and fixed against rotation therewith, a plurality of contact points each having connection with a station of the telephone system mounted on said contact base, a contact arm fixedly mounted on said pivot and 25 cooperable to successively engage said contact points upon rotation of said pivot, a plurality of pairs of numerals on said dial member each pair indicating a station, one numeral of each pair being in inverted relation to the other numeral 30 of that pair, means comprising a screen disposed around said pivot and fixed against rotation therewith for concealing the numerals not in normal reading position, and a signaling key loosely mounted on said shaft and oscillatable in line 40 with movement of said dial, said key having a member extending into the path of movement of the operator's finger.
